G. BROWNING

SPARK PLUG CLEANING APPARATUS

Filed June 30, 1925

GEORGE BROWNING

By *A. B. Bowman*

Attorney

UNITED STATES PATENT OFFICE.

GEORGE BROWNING, OF SAN DIEGO, CALIFORNIA, ASSIGNOR OF ONE-HALF TO ALBERT RICHARDS, OF SAN DIEGO, CALIFORNIA.

SPARK-PLUG-CLEANING APPARATUS.

Application filed June 30, 1925. Serial No. 40,618.

My invention relates to spark plug cleaning apparatus, and the objects of my invention are: first, to provide a spark plug cleaning apparatus whereby spark plugs may be quickly, easily and efficiently cleaned by a blast of granular abrasive without taking the plugs apart; second, to provide a receptacle or tank for a spark plug cleaning apparatus having a working compartment at its lower end adapted to contain sand or other similar granular abrasive, and having a relatively large settling or air separating compartment at its upper portion for effectively separating the sand or other granular abrasive from the air forced therein; third, to provide an apparatus of this class for blasting spark plugs with sand or other granular abrasive in which the air is readily separated from the sand or other granular abrasive without necessarily clogging the air discharge passage, and in which the sand or other granular abrasive is returned to the working compartment and used over and over until substantially all of its abrasive qualities have been destroyed; fourth, to provide an apparatus of this class in which the sand or other granular abrasive blast nozzle may be easily and quickly replaced by another when worn; fifth, to provide an apparatus of this class in which the blast nozzle may be easily adjusted to the proper position relatively to the spark plugs to be cleaned or shifted outwardly beyond the working compartment of the apparatus for applying a sand or other granular abrasive blast on other articles not capable of being inserted into the blast receptacle of the apparatus; sixth, to provide as a whole a novelly constructed spark plug cleaning apparatus, and seventh, to provide an apparatus of this class which is simple and economical of construction, durable, efficient, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a sectional elevational view of my spark plug cleaning apparatus, with the

section taken through 1—1 of Fig. 2; Fig. 2 is another sectional elevational view thereof, taken through 2—2 of Fig. 1, and Fig. 3 is a sectional view thereof in plan, taken through 3—3 of Fig. 1.

Like characters of reference refer to similar parts and portions throughout the several views of the drawings.

The supporting means or frame of my apparatus consists of a small receptacle 1 and a relatively large, upwardly and outwardly diverging or flaring receptacle or tank 2 secured at its lower reduced end to the upper end of the receptacle 1 by means of screws 3, there being preferably placed a gasket 4 between the joining portions of said receptacle, which communicate freely with each other. Extending longitudinally through the receptacle 1 and revolvably mounted therein is a supporting and adjusting screw 5 provided at the end extending beyond the receptacle with a knob 5^a. On this screw 5 is supported a substantially T-shaped fitting 6 by means of an upwardly extending lug 6^a thereon. Through the run portion of the T-shaped fitting 6 extends a long tubular air nozzle 7, which is preferably frictionally secured therein and reciprocally mounted through the wall of the receptacle 1. Said air nozzle 7 is connected to a suitable air hose 8. At the one run end of the fitting 6 is screwably secured the blast nozzle 9, which is positioned around and extends beyond the discharge end of the air injecting nozzle 7, as shown best in Fig. 1. To the lower end of the fitting 6 is secured a tubular member or nipple 10, which extends downwardly from the hollow portion thereof into the sand or other granular abrasive material S placed in the bottom of the receptacle 1. In the one end wall of the working receptacle 1 is mounted a socket member 11 which is adapted to receive the normally inner or ignition end of a spark plug, shown by dotted lines and indicated by P, in the drawings. Near the outer end of the socket member 11 is provided a shoulder 11^a against which is preferably positioned a removable yieldable gasket 12 of a certain size to receive the plug end of the spark plug, the inner shoulder of the spark plug being forced, preferably by hand, against said yieldable gasket.

Near one end of the upper wall of the receptacle 2 is provided a filling opening 2^a.

over which is removably positioned the filler cap 13. In the upper wall of the receptacle 2 is also provided an air discharge opening 2^b surrounded by an upwardly extending 5 and slightly converging flange 2^c over which is positioned the one end of the vent pipe 14, there being preferably provided another flange 2^d around the lower end of the vent pipe 14, as shown best in Fig. 1. This construction 10 around the air discharge opening permits a loose connection between the vent pipe 14 and the receptacle 2 and at the same time permits an automatic seal between the receptacle and the vent pipe by reason of a certain amount of the sand or other abrasive 15 material carried upwardly into the vent pipe and dropping back into the space between the flange 2^c and the vent pipe 14, as shown. Thus it will be seen that when placing the normally inner end of the spark plug into the socket member 11 against the gasket shoulder 12 and forcing air through the nozzle 7, a vacuum will be created at the lower end of the nipple 10, drawing up the sand 20 therein into the fitting 6 and the blast nozzle 9, which sand, together with the air, will be forced against the inner end of the spark plug P, thoroughly cleaning the same of all carbon and oil and at the same time 25 polishing the parts. It will be here noted that the interior of the blast nozzle 9, being constantly subjected to the abrasive action of the sand, will wear down in a short time so as to reduce the efficiency of the apparatus. For this reason I have provided a readily removable blast nozzle which may be unscrewed from the fitting 6, and by shifting the same backwardly by the screw 5, the nozzle 9 may be easily removed.

With this adjustable construction of the nozzle 9, the same may be screwed outwardly beyond the outer end of the socket member 11 by means of the screw 5 so that the apparatus may be used for sand blasting other articles besides spark plugs.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an apparatus of the class described, an upwardly diverging container adapted 60 to receive a granular abrasive material at its bottom end, a blast nozzle positioned within the lower end thereof, communicating with a source of air supply and communicating with the lower end of said container for

drawing upwardly the abrasive material 65 adapted to be positioned therein, and a screw upon which said nozzle is shiftably mounted.

2. In an apparatus of the class described, an upwardly diverging container adapted to 70 receive a granular abrasive material at its bottom end, a blast nozzle positioned within the lower end thereof, communicating with a source of air supply and communicating with the lower end of said container for 75 drawing upwardly the abrasive material adapted to be positioned therein, and a screw upon which said nozzle is shiftably mounted, the discharge end of said nozzle being variously adjustable within said container 80 and extendible beyond the same.

3. In an apparatus of the class described, a container provided with an opening in its wall, a screw revolvably mounted in said container at its lower portion, and an abrasive 85 material blast nozzle shiftably supported by said screw and communicating with a source of air supply and with the lower end of said container, said nozzle being adjustable relative to the opening in the wall of the container.

4. In an apparatus of the class described, a container, a fitting adjustably mounted transversely at the lower end of said container and communicating with the bottom 95 portion thereof, an air nozzle extending through said fitting and communicating with a source of air supply, and an abrasive material blast nozzle readily removably secured to said fitting around the discharge 100 end of said air nozzle.

5. In an apparatus of the class described, a container having a relatively small working compartment at its lower end, and another larger compartment flaring outwardly 105 and upwardly therefrom providing an abrasive material settling and air separating tank, said upwardly and outwardly flaring compartment being provided at its upper end with a free vent to the atmosphere, said lower relatively small compartment being provided with an opening in its end wall adapted to receive a spark plug, an adjusting screw extending longitudinally through said smaller compartment, a fitting shiftably supported on said screw and communicating with the lower end of said compartment, said fitting being provided at its one end with an abrasive blast nozzle directed toward the opening in the wall of the 110 smaller compartment, and an air nozzle extending into said fitting and the blast nozzle and communicating with a source of air supply.

In testimony whereof, I have hereunto set 125 my hand at San Diego, California, this 18th day of June, 1925.

GEORGE BROWNING.
